UNITED STATES PATENT OFFICE.

JOSEF ROSEMEYER, OF LINDENTHAL, GERMANY, AND GUSTAVE DIVE, OF BRESSOUX, BELGIUM.

LONG-BURNING ARC-LAMP.

No. 865,271.

Specification of Letters Patent.

Patented Sept. 3, 1907.

Application filed March 7, 1905. Serial No. 248,793.

To all whom it may concern:

Be it known that we, JOSEF ROSEMEYER and GUSTAVE DIVE, both subjects of the King of Prussia, German Emperor, residing at Lindenthal, near Cologne-on-the-Rhine, in the Province of the Rhine, Kingdom of Prussia, German Empire, and Bressoux, near Liege, in the Kingdom of Belgium, have invented certain new and useful Improvements in Long-Burning Arc-Lamps, of which the following is a full, clear, and exact specification.

This invention relates to certain new and useful improvements in long burning arc lamps, and the novelty resides in the peculiar construction, arrangement and adaption of parts, all as more fully described, shown in the drawings, and then particularly pointed out in the claims.

The new lamp is illustrated in the accompanying drawing as follows:

Figure 1 shows a longitudinal section through the upper part of the lamp, the parts not relating to the present invention such as the resistance, the outer lamp cover, the outer transparent globe and the reflector have been omitted. Fig. 2 is a section on the line A—B of Fig. 1. Fig. 3 is a section on the line C—D of Fig. 1. Fig. 4 is a section on the line E—F of Fig. 1. Fig. 5 is a longitudinal section through the lower part of the lamp.

The upper carbon is marked 1 and the lower carbon 2; 3 indicates the inner glass globe usually employed in long burning arc lamps, which globe surrounds the electric arc and protects the carbons from the action of the outer atmosphere. This globe 3 is hermetically connected with the casing 4 in the following manner: The casing 4 is widened at its lower edge. In this widening is disposed a ring 5 which is insulated by means of the insulation layer 6 from the casing 4. The ring 5 has one side beveled to match the corresponding part of the lower expanded rim of the casing 4. Underneath the ring 5 there is arranged an annular disk 7 above and below which are placed asbestos washers 8 and 9.

The inner glass globe 3 is secured by means of the threaded ring 10 which screws upon a threaded part of the casing 4, and presses from below, with the interposition of an asbestos washer 11, against the widened upper edge of the globe 3 which in turn presses against the asbestos ring 7 so that an air-tight closure is obtained. The ring 5 bears a dish-shaped member 12 in the center of which is suspended the box 13 which serves as the guide for the positive carbon. The holder 15 for the negative carbon 2 is also supported from the member 12 by means of rods 14, 14. At the top of the casing 4 is fixed the tube 16, which reaches upward into the internal cavity of the regulating magnet 17, and is fastened above to the casing 18 surrounding this magnet. The latter is borne by the dome 19

which hangs in the holder 20 and is closed above. The inner glass globe 3, the casing 4, the tube 16, the casing 18 and the dome 19 inclose a space which is air-tight, or as air-tight as it is possible to produce in practical manufacture, in which combination, only a single joining place, namely at 7 is absolutely necessary, so that an extremely good closure is secured for the electric arc and consequently an exceptionally long duration of burning is secured.

The entire lamp casing has only one polarity and that the positive one. The negative current passes from the negative carbon 2 into the lower carbon holder 15 and through the rods 14 and the dish 12, to the ring 5. From this ring it passes by means of a screw 21, which is mounted in an insulated ferrule 22 in the wall of the casing 4, through the conductor 23 to the resistance (not shown in the drawing). The positive current is supplied from the casing 4 by means of the wire 24 to the tube 25, to which the core 26 of the controlling magnet is connected above, which core again carries above a tube 27 serving as the upper carbon holder. The flexible metallic coil 28 which is preferably made of copper, is inserted between the clamping casing 30 and the plate 29 which closed the tube 27 above. The carbon 1 is gripped above by means of the clamp 30, in the head of which the clamping plate 31 is screwed, which holds fast the lower end of the spirally wound wire 28, while the upper end of the latter is held fast by a terminal 32 which is screwed in the plate 29. If the carbon descends, the flexible wire 28 extends and follows the motion of the carbon, so that current is supplied to it constantly and regularly. If a new carbon is inserted an excessive compression of the flexible connection is prevented by means of the bolt 33 which is secured to the bolt 31 and follows this as the carbon sinks. On the insertion of a new carbon, however, the said bolt strikes against the upper terminal 32 and prevents the carbon from being pushed in too much.

It has been already indicated that the interior of the globe 3 and of the casing attached thereto is closed air-tightly. Obviously, however, care must be taken that the internal gases which become heated after the lamp is illuminated and consequently become expanded, can freely escape in order to prevent excessive internal pressure. This is effected in the well known manner by means of a thin tube 34, which permits of the expansion of the interior gases but prevents, during the working of the lamp, the entrance of the outer atmosphere. In order also to prevent entrance of air in the periods of inactivity there is provided a valve 35 in a channel 36, the little tube 34, Fig. 4 communicates with said channel, is bent downwards and has underneath an exit aperture. The valve 35 closes by its own weight the channel 37 leading from the interior of the casing 4 to the

channel 36, but when the lamp is in operation the valve is raised by the pressure of the expanding gases so that the connection with the tube 34 and thereby with the atmosphere is effected. If, however, the lamp is inactive, then the entrance of air into the interior of the lamp casing is prevented by said valve and thereby the great combustion of carbon at the switching in of the lamp is checked. A washered cap 38 is necessary in order to admit of the insertion of the valve 35.

10 The clamping device which serves in the well known manner on the rising and falling of the magnet core 26 to grip the carbon and to raise it or to release it, so that it can slide along, is attached to the lower end of the tube 25, this lower end is constructed as a piston 39 which moves in the casing 4 as cylinder and serves to damp jerking motions. The clamping device consists of the three clamp levers 40, 41 and 42 which at their outer ends are connected together through the joints 43, 44 and 45 with the piston 39, while the inner 20 curve-shaped ends grip the carbon 1. If, in consequence of increasing resistance in the arc, the magnet core 26 sinks down, then the inner lower ends of the clamp levers 40, 41, 42 contact with a fixed plate 46 placed under the same, whereby the clamp levers are 25 swung upwards owing to the weight of the movable core coming upon the pivots 50, and are thus moved out of engagement with the carbon 1 so that the carbon can slip. As the magnet core rises the clamping levers swing again downwards and thereby again grip the 30 carbon, so that the latter will be lifted. Obviously it is necessary that the curved shape of the lower edges of the clamp levers should be such that the above described action can take place. In this arrangement the device which, when the core rises, and the clamp 35 levers 40, 41 and 42 swing together, secures under all circumstances the certain gripping of the carbon is especially novel and important. This action is attained by the central coiled spring 47 which presses above against the tube 25 and below against the plate 40 48. The latter is movable and rests upon the inner ends of the clamp levers 40, 41 and 42. This arrangement of the spring is the more sure because it also does not interfere with the play of the clamp levers if the spring should fail to operate for any reason, because in 45 that case the clamp levers would nevertheless sink down by their own weight. Obviously only one or two clamps might be used, but three have proved better in practice.

In order that the core of the regulating magnet may 50 be very sensitively regulated, friction in the guide must be avoided as much as possible. For this purpose the tube 27 which is attached above to the core 26, is guided by rollers 51, 52, 53 in order to diminish friction owing to the side pull of the magnet field, which is al- 55 ready well known in connection with ordinary arc lamps. The spool core is equally supported from all sides and there is only the slight friction to be overcome

which occurs in the pivots of the bearings. The rollers 51, 52 and 53 are attached to the head of a projection 49 which is rigidly connected with the casing 18. 60

Having thus described my invention what I claim is:

1. In an arc lamp a casing of conducting material closed at one end and open at the other, provided with an aperture near the open end, a ring of insulating material in the latter end, an annular conducting member supported in said insulating material, a lower carbon holder formed of conducting material and having a portion adapted to contact with said annular conducting member, an insulating bushing in said aperture, a conducting member extending through said bushing into contact with said 65 annular conducting member, and a globe inclosing the carbon holder and secured to the casing,

2. In an arc lamp, a casing of conducting material closed at one end and open at the other, provided with an aperture near the open end, a ring of insulating material 75 in the latter end, an annular conducting member supported in said insulating material, a lower ring formed of conducting material and having a portion adapted to contact with said annular conducting member, an insulating bushing in said aperture, a conducting member extending through said bushing into contact with said 70 annular conducting member, and a globe inclosing the carbon holder and secured to the casing, and a guide for the positive carbon carried by the lower end of said ring.

3. In an arc lamp, a casing of conducting material 80 closed at one end, open at the other, provided with an aperture near the open end, a ring of insulating material in the latter end, an annular conducting member supported in said insulating material, a lower ring formed of conducting material and having a portion adapted to 85 contact with said annular conducting member, an insulating bushing in said aperture, a conducting member extending through said bushing into contact with said annular conducting member, and a globe inclosing the carbon holder and secured to the casing, said ring being 90 conical shaped, a guide for the positive carbon, carried by the lower end of said ring, and a holder for the negative carbon supported from said ring.

4. In an arc lamp, a casing of conducting material closed at one end, and open at the other, provided with an aperture near the open end, a ring of insulating material in the latter end, an annular conducting member supported in said insulating material, a lower ring formed of conducting material and having a portion adapted to contact with said annular conducting member, an insulating bushing in said aperture, a conducting member extending through said bushing into contact with said 100 annular conducting member, and a globe inclosing the carbon holder and secured to the casing, said ring being conical shaped, a guide for the positive carbon, carried by the lower end 105 of said ring, and a holder for the negative carbon supported from said ring, said globe being held directly to the casing and hermetically connected therewith, and the insulated screw connected with the parts of negative polarity insulated within said casing.

In testimony whereof we have signed our names to this specification in the presence of two subscribing witnesses.
